UNITED STATES PATENT OFFICE.

JAMES C. CRANIGER, OF KANE, PENNSYLVANIA.

VAPOR-BURNING STREET-LAMP.

SPECIFICATION forming part of Letters Patent No. 690,237, dated December 31, 1901.

Application filed June 12, 1901, Serial No. 64,280. (No model.)

To all whom it may concern:

Be it known that I, JAMES C. CRANIGER, a citizen of the United States, residing at Kane, in the county of McKean and State of Pennsylvania, have invented new and useful Improvements in Vapor-Burning Street-Lamps, of which the following is a specification.

My invention relates to liquid-fuel street-lamps; and the objects of the same are to construct a lamp of this character which will be simple in construction and economical and efficient in operation. To accomplish this, I have provided, first, an improved vaporizing-coil; second, an auxiliary burner for heating said coil while the main burner is out and for relighting the same; third, an automatic means for cutting off and relighting either of the burners, and, fourth, an improved shade to protect the lamp from wind and snow.

The novel construction by which these improvements are carried out is fully described in this specification and claimed, and illustrated in the accompanying drawings, forming a part thereof, in which—

Figure 1 is an elevation, partially in section, of my lamp and shade. Fig. 2 is a vertical longitudinal section of the same. Fig. 3 is a diagrammatic view showing my lamp mounted on a post and the tank for holding a supply of gasolene. Fig. 4 is a detail vertical section of the valve. Fig. 5 is a detail plan of the same. Fig. 6 is a detail horizontal section of the same.

Like numerals of reference designate like parts in the different views of the drawings.

The numeral 1 designates a tank for containing a supply of gasolene or other light oil under pressure, which pressure is maintained by forcing a supply of air into a pipe 2, supplied with a valve 2^a. A supply-pipe 3 passes through the top of tank 1 and down to within a short distance of the bottom. The feed-pipe 3 is of small size and extends up to a lamp 4, suspended from a bracket 4^a, secured to a lamp-post 6 of ordinary construction. The parts of the lamp 4 are supported by a frame 5, which comprises side bars 6 and 7, connected by cross-bars 8 and 9 and an intermediate cross-bar 10.

The intermediate cross-bar 10 is made in four sections, a middle hollow section 10^a and a solid section 10^b, a perforated section 10^c, and

a hollow section 10^d. The section 10^d is made of pipe and is connected to the side bar 6, which is also made of pipe, plugged at its upper end at 11 and connects with a vertical burner-pipe 12. The section 10^a serves as a vapor or vaporizing chamber and is provided with a casing 10^e, fitted therein and having thereon a series of graduated steps 10^f to prevent the flow of liquid gasolene therethrough and retain it till vaporized. The perforated member 10^c forms an air-mixing chamber. The bar 10 serves to support a vaporizing-coil 13, consisting of two coils 13^a and 13^b, made of large and small pipe, respectively, wound conical and parallel to each other, thereby forming a frusto-conical coil open at both ends. The large pipe is about one-half an inch in diameter and the small pipe about one-eighth of an inch. The coils 13^a and 13^b are made continuous by joining the upper ends of the large and small coils. The lower end of the small coils 13^b is connected at 13^c to the section 10^a.

The large end of the coil 13 is about four inches in diameter and opens downward directly over a burner to be described. The vertex of the conical coils is open, and mounted within this opening is an auxiliary heating-burner 14.

The burner 14 is designed to be kept lighted while the main burner is out and to ignite the main burner. Means for automatically lighting and shutting off the burner will be hereinafter described. The auxiliary burner 14 is constructed of a perforated tip 15, mounted on the end of a small pipe 16 and connected to an apertured perforated casing 17, extending down into the coils 13. A small heating-coil 18 is formed in the pipe 16 and surrounds the casing. This arrangement increases the heating of the gasolene before passing to the burner 14 after it is once under headway.

The main burner is designated by the numeral 19 and is detachably connected to the burner-pipe 12. The burner 19 has a wire-gauze 20, which is covered by a mantle 21, suspended from an arm 21^a. An air-shield 22 and arms 23 for supporting a chimney are mounted on the burner 19. The burner 19 is located directly under the coil 13, and thus serves to heat it and vaporize the gasolene before it reaches the burner. A pipe 23^a is con-

nected to the frame just beneath the burner 19 and forms a trap to catch the refuse from the burner.

Two burners have now been described which 5 have been termed the "main" burner 19 and the "auxiliary" burner 14. The main burner is connected to the coils 13 through the medium of the side bar 6 of the frame 5, while the auxiliary burner is provided with its own 10 heating-coil 18.

To regulate the flow of gasoline from the reservoir 1 to the burners, a two-way valve is connected to the feed-pipe 3. This valve has a casing 24, in which, mounted to turn, is a 15 conical valve 25, having ports 26, 27, and 28, designed to make connections with passage 26^a, 27^a, and 28^a, respectively, in the casing 24. The port 26 is wide enough to communicate with the passage 26^a when either of the 20 other ports 26 or 27 are connected with their corresponding passages. The ports 27 and 28 are so arranged that both can make partial connections at the same time. This corresponds to the time when the oil is flowing 25 to both burners, as will appear. The valve 25 is provided with a lever-arm 29 for operating it. The passages 26^a, 27^a, and 28^a are connected to the feed-pipe 3, the pipe 16, leading to the auxiliary burner, and a pipe 30, con-

30 nected to the lower end of the large coil 13^a. By this arrangement it is evident that in the extreme position of the lever 29 gasoline will be supplied to one burner, but at the intermediate position it will be supplied to both.

35 The lever 29 may be operated by means of pendent wires; but for street-lighting an automatic device for turning it on and off is a great convenience. For this purpose a mechanism now to be described is provided.

40 A disk 31 is mounted vertically on a longitudinal shaft, which is the hour-hand sleeve of a clock 32 of ordinary construction. By this means the disk 31 is revolved once every twenty-four hours. The face 33 of the disk 45 31 is composed of twenty-four detachable sections of three different kinds. The sections of the first class are designated 33^a and are each cut by a circular groove 34^a of large radius and subtending fifteen degrees. The 50 second class of sections are designated 33^b and have grooves 34^b thereon subtending an arc of fifteen degrees each, but of smaller radius. The third class of segments 33^c consist of two members which are cut by diagonal grooves 34^c, which serve to connect the grooves 34^a and 34^b. These sections are set, as shown, with the grooves 34^a, 34^b, and 34^c forming one continuous groove. The 55 number of each of the series 33^a and 33^b may be changed, depending on the time the light is to be lighted; but there are always two sections 33^c. The lever 29 is set to engage the grooves 34 in the disk 31, which on turning will operate it. When the lever is engaged by the 60 groove 34^a the gasoline will be flowing to the main burner 19, when it is engaged by the groove 34^b gasoline will be flowing to the

auxiliary burner 14, and when it is engaged by the diagonal grooves 34^c gasoline will be flowing to both burners and one can light the 70 other.

A cylindrical casing 35 is placed around the coils 13 and serves to confine the heat and to protect the valve 24 and clock 32 therefrom. To provide an additional protection, a double circular sloping roof 35^a is suspended from the bar 10. The upper layer 35^b of the roof 35^a is apertured in the center and is parallel and separate from the lower layer 35^c, which is apertured in the center 80 and perforated. The upper roof 35^b bears a downwardly-extending pipe 35^d, which passes through the aperture in the lower roof 35^c and fits snugly the burner-chimney. Fitting snugly over the roof 35^a is a dome-shaped 85 metal shade 36, apertured at 37 and provided with a cover 38. A pair of concentric parallel perforated disks 39 are mounted just below the burner 19 and serve to support an inverted-bell-shaped shade 40, which extends 90 up and has its upper edge covered by the roof 35^c. By this combination of the roof 35^a, shade 36, and shade 40 the heat of the burner is confined and directed against coils 13 and pipe 10^a and the gasoline completely vaporized.

In operation the tank 1 is half filled with gasoline and air pumped in until a pressure of from twenty to forty pounds is obtained. The valve 24 is then set to admit gasoline to the auxiliary burner 14, which is then lighted. The flame from this burner will soon heat the small coil 18, and the burner will give off a pale blue flame, which will be directed by the casing 17 against the coils 13^a and 13^b, heating them. The lever 29 is now set at its intermediate position and gasoline admitted to both burners. The gasoline will flow from the burner 24 through the pipe 30 into the large coils of large pipe 13^a at the bottom of the coil 13, then through this pipe to the top of the coil, then into the coils of small pipe 13^b, down through this pipe to the bottom of the coil, after which it will pass on through the pipe 10^a and become mixed with air, after 115 which it will go to the burner 19. As soon as the gasoline vapor reaches the burner 19 the flame from the burner 14 will light the burner 19. The flame from the burner 19 will then heat the coils 13 to a very high temperature, which will insure the complete vaporizing of the gasoline and produce a very bright clear light. After the lighting of the burner 19 the gasoline is completely cut off from the burner 14 by means of the lever 29. 120 When it is desired to extinguish the burner 19, the lever is set at its intermediate position until the burner 14 is lighted by the flame of 19, after which the gasoline is cut off from the large burner. The flame of the 125 small burner will keep the coils 13 hot, so there need be no delay in relighting the burner 19. If the clock is employed, the diagonal grooves of the disk 31 will insure a supply

of gasolene to both burners long enough for one to light the other.

The perforated roof 35° fits closely the shade 40; but the perforations therein permit 5 the escape of the heated air and keep the shade 40 cool, so that snow or rain in striking it will not cause breakage.

I do not wish to be limited as to details of construction, as these may be modified in 10 many particulars without departing from the spirit of my invention.

Having described my invention, what I claim as new, and wish to secure by Letters Patent, is—

15 1. In a device of the class described, the combination with a burner provided with a feed-pipe, of a frusto-conical coil located immediately over said burner, large end down, and connected to said feed-pipe, a vaporizing-chamber extending transversely the large 20 end of said coil, an auxiliary burner located directly over said burner within the small end of said coil, and constructed to provide a flame to heat said coils and said vaporizing-chamber and to be ignited by said burner and 25 to ignite the same, substantially as described.

2. In a device of the class described, the combination with a burner provided with a feed-pipe, of a conical coil comprising coils 30 of larger and smaller pipe and located immediately over said burner, large end down, and connected to said feed-pipe, and an auxiliary burner comprising a pipe coiled around and connected to an open-mouthed casing 35 located within the small end of said coil and directed downwardly, substantially as described.

3. In a device of the class described, the combination with a burner provided with a feed-pipe, of a conical coil formed of a plurality of coils of large and small pipe, said coil being located immediately over said burner, a vaporizing-chamber extending transversely said coil and connected to the

coils of small pipe thereof, substantially as 45 described.

4. A vaporizing-coil comprising a plurality of coils of large pipe, a plurality of coils of smaller pipe wound on the outside of said coils of large pipe, substantially as described. 50

5. In a device of the class described, the combination with a two-way valve provided with a lever and connected to a feed-pipe, of a burner, a coil located over said burner and connected to said two-way valve and to said 55 burner, an auxiliary burner connected to said valve and located to heat said coil and to be lighted by said first-mentioned burner, a disk provided with a groove engaging said lever, and means for revolving said disk, substantially as described.

6. In a device of the class described, the combination with a burner provided with a chimney, of a perforated disk mounted beneath said burner, a shade resting on said 65 disk, a centrally-apertured, sloping, perforated lower roof resting on said shade, an upper sloping roof bearing a pipe which extends through the aperture in said lower roof and fits over said chimney, and a shade 70 fitting over said upper roof, substantially as described.

7. In a device of the class described, the combination with a burner of a vaporizing-coil located over said burner and connected 75 at one end to a feed-pipe, a vaporizing-chamber provided with a graduated series of steps and connected to the other end of said coil, and an air-mixing chamber connected to said vaporizing-chamber, substantially as de- 80 scribed.

In testimony whereof I have hereunto set my hand in presence of two subscribing witnesses.

JAMES C. CRANIGER.
